INVENTOR.
JOSEPH ALEXANDER MAYERS

BY
John S. Hubble
ATTORNEY

UNITED STATES PATENT OFFICE

JOSEPH ALEXANDER MAYERS, OF CUMBERLAND, MARYLAND; TAYLOR MORRISON
EXECUTOR OF SAID JOSEPH ALEXANDER MAYERS, DECEASED

HUMIDIFYING APPARATUS

Application filed September 19, 1928. Serial No. 306,864.

The present invention relates to air conditioning apparatus and in particular to apparatus for humidifying the atmosphere of a building by the introduction of steam into the room atmosphere. The object of my present invention is to provide an improved construction and arrangement of the various elements comprising the humidifier.

The various features of novelty which characterize my invention are pointed out with particularity in the claims annexed to and forming a part of this specification. For a better understanding of the invention, however, and the advantages possessed by it reference should be had to the accompanying drawing and descriptive matter in which I have illustrated and described preferred embodiment of the invention.

Of the drawing:

- 20 Fig. 1 is an elevation of one form of my invention;
Fig. 2 is a similar view of a modified form;
Fig. 3 is an enlarged elevation in section of the mixing device; and
25 Fig. 4 is an enlarged elevation partly in section of the regulating valve shown in Fig. 2.

In the drawing and particularly in Fig. 1, I have illustrated a preferred embodiment 30 of my invention in which a reservoir chamber A is connected by a pipe A' having a regulating valve A² to a source of water, such as a city supply main. As shown, the pipe A' is connected to the top of the reservoir chamber and the incoming water drops into the chamber. A constant water level is maintained in the reservoir by the connection thereto of an overflow pipe B at the desired level.

40 A water outlet pipe C is connected to the reservoir chamber at a point slightly below the water level therein, whereby a constant flow of water is maintained. A regulating valve or cock D is mounted in the pipe line 45 C. The valve D is so adjusted that a predetermined amount of water drips from the end of the pipe C into a funnel E positioned below the pipe end. The funnel E is connected by a pipe F to an enclosed flash boiler chamber shown in Fig. 1 as a heating coil

G located in a refractory housing H. A fluid fuel burner J is arranged in the housing below the heating coil and a flue gas outlet H' provided in the housing top. A fuel supply pipe J' having a regulating valve J² therein 55 is connected to the burner. The housing is open at the bottom to provide sufficient air for combustion. The burner flame is prevented from being extinguished when the housing is connected to the building chimney 60 by a down draft protector H² positioned over the housing opening H'.

The lower end of the heating coil G is connected by a pipe G' to a steam discharge pipe K, the lower end of which is located in 65 a water seal M and the upper end of which passes through the floor K' into the room in which the atmosphere is to be humidified. An overflow pipe M' is attached to the seal M adjacent the upper end thereof. The overflow pipe B connects with the pipe K just above the water seal.

As shown in Figs. 1 and 3, a mixing device L is mounted on and surrounds the upper end of the steam discharge pipe K. The mixing 75 device comprises a tapered nozzle L' positioned in the upper end of the pipe K with the tapered discharge end of the nozzle positioned in an open ended cylinder L². A bowl L³ is secured to the pipe K with the upper 80 portion of the bowl surrounding the lower end of the cylinder L². The cylinder is suitably supported by and spaced from the sides of the bowl. Steam passing upwardly through the nozzle L' and marginal openings 85 L⁴ formed therein is mixed in the cylinder L² with air drawn in below the lower end of the cylinder. Any condensate collecting on the sides of the cylinder drops into the bowl L³ and accumulates in the bottom thereof 90 until the liquid reaches the level of and overflows into the upper end of the pipe K. The condensate passes downwardly through the marginal openings L⁴ to the sealing apparatus.

The pipes B and F are arranged with depending U-shaped portions B' and F', respectively, adjacent the connections of said pipes to the pipe K and heating coil G. The tube portions B' and F' act as traps to pre- 100

vent the passage of steam upwardly through the pipes B and F respectively. The portions of the pipes B and F above the U-shaped portions B' and F' are preferably made of sufficient length to permit the water in the 6 U-shaped portions to back up under the pressure of the steam in the boiler chamber without overflowing. In the embodiment illustrated this length is preferably as great as the 10 portion of the pipe forming the outer leg of the U-shaped portion.

With the apparatus arranged as described water under pressure is passed into the reservoir chamber A from a water supply main, 15 the pressure in which may vary as much as 20%. The overflow pipe B maintains a constant head on the pipe C and when the cock D is properly adjusted, the water drips down into the funnel E at a constant rate of flow, 20 for example, at about twenty drops per minute which will be sufficient to properly humidify a dwelling house of ordinary size. Passing downwardly the water enters the steam generating coil G where it is heated 25 by the up-flowing combustion gases. By the time it reaches the high temperature zone at the bottom of the coil sufficient heat has been added to the water to evaporate the water and the steam generated passes off 30 through the pipe G' to the steam outlet pipe K. The steam is then mixed with air in the nozzle L, cooled by the air, and the mixture discharged into the rooms to be humidified. The products of combustion are maintained 35 separate from the steam generated, and are carried off to the house chimney in any suitable manner. Any water passing downwardly in the overflow pipe B will be conveyed to the water seal which also receives any condensate forming in the pipe K. With the above rate of water flow, the fuel regulating valve J is adjusted² until approximately one and one-half cubic feet of natural gas is passed to the fuel burner per hour.

45 In the modification illustrated in Fig. 2, the reservoir chamber A and overflow pipe B are eliminated and a special regulating valve P utilized to maintain a constant rate of flow of water from the source of supply to the funnel E. As shown in Fig. 4, the valve P is provided with a porous compressible piece of felt P' which is secured to the bottom of the valve disc P² and is so adjusted that the water seeps through at the desired rate.

55 In this modification I have illustrated another form of flash boiler which may be used in place of the heating coil G. The coiled tube shown in Fig. 1 is replaced by a closed cylindrical chamber R. As the water passes 60 into the chamber from the pipe F it immediately flashes into steam in contact with the heated bottom surface of the chamber and passes out through the steam discharge pipe G'.

65 While in accordance with the provisions

of the statutes, I have illustrated and described the best form of embodiment of my invention now known to me, it will be apparent to those skilled in the art that changes may be made in the form of the apparatus disclosed without departing from the spirit of my invention as set forth in the appended claims and that in some cases certain features of my invention may be used to advantage without a corresponding use of other 75 features.

Having now described my invention what I claim as new and desire to secure by Letters Patent, is:

1. A humidifier comprising in combination 80 a closed flash boiler, means for passing water at a constant rate to said boiler, a fluid fuel burner for heating said boiler, a steam discharge pipe connected to said boiler and having its discharge end opening to the space 85 to be humidified, and a mixing nozzle surrounding the discharge end of said pipe for mixing air from said space with the steam before its discharge into said space.

2. A humidifier comprising in combination 90 a closed flash boiler chamber, means for passing water at a constant rate to said chamber, said means consisting of a reservoir connected to a source of supply, an overflow pipe connected to said reservoir at a predetermined level therein, a water outlet pipe connected to said reservoir at a point below the normal water level therein and a pipe having a U-shaped depending portion passing water from said water outlet pipe to said boiler 95 chamber, a fluid fuel burner below said chamber, a steam discharge pipe connected to said chamber and having its upper end open to the space to be humidified and its lower end submerged in a water seal, and said overflow 100 pipe being connected to said water seal.

3. A humidifier comprising in combination 110 a closed flash boiler chamber, a fluid fuel burner below said chamber, means for passing water at a constant rate to said chamber comprising a water inlet pipe connecting the upper end of said boiler chamber to a source of supply, said inlet pipe having a depending portion below the level of the connection of said pipe to said boiler chamber, and a steam discharge pipe connecting the lower end of said boiler chamber to a room to be humidified and maintaining said steam separate from the products of combustion.

4. A humidifier comprising in combination 120 a closed flash boiler chamber, means for passing water at a constant rate to said chamber comprising a water inlet pipe connecting the upper end of said boiler chamber to a source of supply, said inlet pipe having a depending portion below the level of the connection of said pipe to said boiler chamber and an upper portion of approximately 125 the length of one of the legs of said depending portion, and a steam discharge pipe con- 130

necting the lower end of said boiler chamber to a room to be humidified and maintaining said steam separate from the products of combustion.

5 5. Humidifying apparatus comprising in combination a steam generator, a steam outlet pipe connecting said generator to the space to be humidified, and an air and steam mixing device in said space mounted on the
10 discharge end of said outlet pipe and comprising a bowl surrounding the upper end of said pipe, a tubular member positioned within and spaced from the sides of said bowl above said pipe to permit the passage of air
15 from said space into the lower end of said tubular member, and an injector nozzle in the discharge end of said pipe and extending into the lower end of said tubular member, whereby a circulation of air and steam through said
20 tubular member is provided.

Signed at Cumberland in the county of Allegany and State of Maryland, this seventeenth day of September, A. D. 1928.

JOSEPH ALEXANDER MAYERS.
